UNITED STATES PATENT OFFICE.

GIRARD GRANVILLE NAUGLE, OF YORK, PENNSYLVANIA.

TRAIN-STOPPING APPARATUS.

1,135,910.

Specification of Letters Patent. Patented Apr. 13, 1915.

Application filed May 26, 1914. Serial No. 341,123.

To all whom it may concern:

Be it known that I, GIRARD G. NAUGLE, a citizen of the United States of America, residing at York, in the county of York and 5 State of Pennsylvania, have invented new and useful Improvements in Train-Stopping Apparatus, of which the following is a specification.

This invention relates to improvements in 10 train stopping apparatus and has particular application to the car carried mechanism of such apparatus.

In carrying out the present invention, it is my purpose to provide automatic train 15 stopping apparatus wherein the throttle valve lever and the engineer's brake valve will be under the influence of motors adapted to be placed in operation when the train enters the danger zone whereby the throttle 20 valve will be closed and the engineer's brake valve operated to cut off the flow of steam to the drive cylinders and effect an application of the brakes to the wheels.

It is also my purpose to provide apparatus 25 of the class described wherein by means of an indicator or counter, the proper road officials may determine the number of times the train stopping apparatus has been brought into service.

30 A further object of the invention is the provision of apparatus of the type set forth which will embrace the desired features of simplicity, efficiency, and durability, which may be installed and maintained at a minimum expense and which will operate effectively under all conditions.

With the above and other objects in view, the invention consists in the construction, combination and arrangement of parts hereinafter set forth in and falling within the 40 scope of the claims.

In the accompanying drawings; Figure 1 is a longitudinal sectional view through the throttle valve actuating motor, the throttle valve lever being shown in side elevation. 45 Fig. 2 is a similar view through the engineer's brake valve actuating motor, the brake valve being shown in top plan. Fig. 3 is a diagrammatic view of the car carried 50 mechanism. Fig. 4 is a view in elevation of the indicating device, the cover of the casing being removed and parts shown in

section. Fig. 5 is a view in side elevation of the indicator. Fig. 6 is a view in end elevation thereof. Fig. 7 is a top plan view 55 of the latch bar of the indicator. Fig. 8 is a cross sectional view through the controlling valve of the apparatus. Fig. 9 is a diagrammatic plan view of a portion of the car carried mechanism.

Referring now to the drawings in detail, 60 1 designates the throttle valve rod of a locomotive, while 2 indicates a bracket secured to the end of the boiler within the locomotive cab adjacent to the outer end of the rod 1 and extending outwardly from the boiler parallel with the rod. Extending upwardly from the bracket 2 is an arm 3 and pivoted upon the arm 3 is the upper end of the throttle lever 4, such lever being formed 70 with a slot 5 in which works a pin 6 carried by the rod 1. Thus, when the throttle lever is swung about its pivotal connection with the arm 3 in one direction the rod 1 will be moved to close the throttle valve, while 75 when the lever 4 is swung in the opposite direction a pull will be exerted upon the rod 1 with the effect to move the throttle valve to open position. Suitably connected with the outer end of the bracket 2 is a 80 motor comprising, in this instance, a horizontal cylinder 7 within which is mounted for sliding movement a piston 8 and connected with the piston 8 and projecting outwardly of the inner end of the cylinder is 85 a hollow piston rod 9 surrounding the outer end of the throttle valve rod 1, while encircling the piston rod 9 within the cylinder is a coiled expansion spring 10 having one end abutting the inner head of the cylinder 90 and the opposite extremity engaging the confronting face of the piston, such spring acting to hold the piston normally at the outer end of the cylinder 7 whereby the throttle valve lever 4 may be freely manipulated 95 by the engineer, the rod 1 sliding back and forth within the piston rod 9 in the manual operation of the throttle valve under the action of the lever 4.

11 designates the engineer's brake valve 100 by means of which the air brake system of the train is controlled and connected with the handle of such valve and extending outwardly therefrom coextensively therewith is

an arm 12 having one side edge formed with a depression 13, while disposed in proximity to the engineer's brake valve is a motor comprising, in the present instance, a horizontal cylinder 14 and within which is mounted for sliding movement a piston 15 equipped with a piston rod 16 projecting outwardly of one end of the cylinder and adapted, when moved under the action of the piston 15 in one direction, to engage the depression 13 in the arm 12 and swing the latter with the effect to actuate the brake valve to bleed the brake pipe or train line air pipe of the brake system whereby the brakes will be applied to the wheels of a car or train. Surrounding the piston rod 16 within the cylinder 14 is a coiled expansion spring 17 having one end abutting the inner head of the cylinder, that is, to say, the head of the cylinder adjacent to the brake valve, and the opposite extremity in engagement with the confronting face of the piston 15, such spring acting to maintain the piston 15 normally at the outer end of the cylinder 14.

The cylinders 7 and 14 of the motors are connected with a fluid conducting pipe 18. Depending from the locomotive or other motor car is a bracket 19 and connected to the bracket 19 and supported thereby is a controlling valve 20 comprising a casing 21 having a horizontal bore 22 formed therein provided with right angular ports 23, 24. Leading from the port 23 is a pipe 25 connected with the pipe 18, while connecting the port 24 with the main air reservoir of the air brake system of the car or train is a pipe 26. Rotatably mounted within the bore 22 is a plug 27 formed with a substantially V-shaped cavity 28 adapted when the plug is in one position to establish communication between the ports 24 and 23 whereby the cylinders 7 and 14 of the motors will be placed in communication with the main air reservoir, and when in another position, to establish communication between the port 23 and the atmosphere by way of a vent opening 29 formed in the casing 21 whereby the fluid in front of the pistons in the cylinders 7 and 14 may be exhausted to the atmosphere. Extending outwardly from one end of the plug 27 is a stem and connected with the stem and depending therefrom is a handle 30 lying normally in a vertical plane. Normally, the plug 27 is in such a position that the cavity 28 therein establishes communication between the port 23 and the vent aperture 29 thereby maintaining the ends of the cylinders 7 and 14 in communication with the atmosphere, the springs 10 and 17 within such cylinders holding the pistons at the forward ends thereof. On the other hand, when the handle 30 is rocked to rotate the plug 27 within the bore 22 in the casing 21, the cavity 28 in such

plug establishes communication between the ports 24 and 23 and cuts off communication between the port 23 and the atmosphere. Thus, the cylinders 7 and 14 are placed in communication with the source of supply and the pistons within such cylinders actuated against the action of the springs there-in with the effect to swing the throttle valve lever and close the throttle valve and actuate the engineer's brake valve to apply the brakes.

Mounted one above the other and suitably connected to the under surface of the locomotive or motor car are horizontal bearings 31 disposed in advance of the forward and rear of the handle 30 and slidably mounted within the upper bearing 31 is a horizontal rod 32, while similarly mounted within the lower bearing is a horizontal rod 33. The rear ends of the rods 32 and 33 contact with the forward edge of the handle 30, while disposed between the forward ends of such rods is a support 34 and fulcrumed upon such support is a vertical lever 35 formed, above and below the fulcrum point thereof with slots 36, 37 respectively within which work pins 38 carried by the forward ends respectively of the rods 32 and 33. Arranged at the opposite sides of the lever 35 are retractile springs 39 having the lower ends thereof connected with the lever and the upper ends connected with the support 34 and such springs act to hold the lever 35 normally in a vertical position and restore the same to such position succeeding the swinging of the lever. By means of this construction, it will be seen that when pressure is applied to the front edge of the lever 35 at the lower end thereof, such lever will be swung about its pivot point in one direction whereby the rod 33 will slide rearwardly and the rod 32 forwardly and as the rod 33 slides rearwardly the handle 30 of the valve 20 is swung to rotate the plug 27 to establish communication between the source of supply and the cylinders 7 and 14 as previously described. On the contrary, when pressure is applied to the rear edge of the lever 35 adjacent to the lower end thereof the rod 33 slides forwardly and the rod 32 rearwardly whereby the handle 30 of the valve is swung to rotate the plug 27 to establish communication between the source of supply and the cylinders of the motor, the springs 39 serving to restore the lever 35 to normal vertical position succeeding the release thereof.

In order to swing the lever 35, suitable track obstacles are employed and arranged along the trackway at the necessary points and rendered active when traffic conditions warrant and normally held inactive. Thus, it will be seen that when a motor car is moving in a forward direction, the forward

edge of the lever 35 will engage an active obstacle, while when the car is traveling rear end first, or the normal direction of traffic reversed, the rear edge of the lever 35 will engage the active track obstacle, the springs 39 restoring the lever to normal position when such lever is relieved of the influence of the obstacle.

The free end of the plug 27 is provided 10 with an outwardly projecting shank and connected with such shank and extending upwardly therefrom is an arm 40 designed to swing with the arm 30 and disposed adjacent to the forward end of the path of movement of the arm 40 is a casing 41 arranged transversely of the car and supported in any suitable manner. Slidably mounted within horizontally alining bearings mounted within the casing 41 adjacent to the bottom 20 wall thereof is a horizontal latch bar 42 having one end thereof working within a slot 43 formed in one edge wall of the casing and the projecting end of the latch bar lies in the path of the arm 40, while interposed 25 between the inner end of the latch bar and the adjacent edge wall of the casing 41 is a coiled expansion spring 44 having one end abutting the inner end of the bar and suitably fastened thereto and the opposite end 30 engaging the edge wall of the casing and secured thereto. As the arm 40 swings in the rotation of the plug 27 of the controlling valve, such arm engages the outwardly projecting end or nose of the latch bar 42 and 35 slides the latter into the casing 41 against the action of the spring 44 and when the rear edge of the arm 40 passes the nose on the latch bar the spring 44 reacts to restore the latch bar to normal position thereby 40 locking the arm 40 against return to normal position and maintaining the plug 27 of the controlling valve 20 in actuated position whereby communication between the source of supply and the cylinders 7 and 11 of the 45 motors is maintained. In order to relieve the arm 40 of the influence of the latch bar 42, one side of the latter is equipped with an outwardly extending pin 45 designed to work within a slot in one side wall of the 50 casing 41 and equipped with a knob 46. When the knob 46 is grasped by the hand 55 pressure may be applied to the pin 45 to slide the bar 42 into the casing against the action of the spring 44 and thus release the arm 40 whereby the controlling valve will be restored to normal condition and communication established between the cylinders 7 and 14 and the atmosphere.

Journalized in the opposite side walls of 60 the casing 41 above the latch bar is a shaft 47 and fast to the shaft 47 is a counterwheel 48 having one face thereof marked with a series of consecutive parts arranged concentrically of the axis of the disk and spaced

apart and each capable of movement into 65 registration with a sight opening 49 formed in the adjacent side wall of the casing. Fast upon the shaft 47 is a ratchet wheel 50 having every two teeth thereon equal in length to the spaces between the annulus on the 70 face of the counterwheel and engaging the teeth of the ratchet wheel is a spring pressed dog 51 carried by the latch bar 42 and preferably mounted within a recess therein. Also engaging the teeth of the ratchet wheel and 75 pivoted to the adjacent side wall of the casing 41 is a holding dog or pawl 52. In the inward movement of the latch bar 42 under the action of the arm 40 the dog 51 acts upon the adjacent tooth of the ratchet wheel 80 50 to rotate the latter through the distance of one tooth and as the springs 44 react to restore the latch bar to latching position after the arm 40 has passed over the same the dog 51 idles over the teeth of the ratchet 85 wheel 50 and the dog 52 holds the ratchet wheel 50 against retrograde movement. In the movement of the latch bar under the action of the knob 46 and pin 45 to release the arm 40, the dog 51 again rotates the 90 ratchet wheel 50 through the distance of one tooth and these two movements of the ratchet wheel rotate the counterwheel 40 a distance equal to the space between the bars thereon visible through the sight opening 49 and the 95 adjacent bar thereby bringing the next bar into view so that the number of times that the apparatus has been brought into service may be determined.

From the foregoing description taken in 100 connection with the accompanying drawings, the construction, mode of operation and manner of employing my invention will be readily apparent. It will be seen that I have provided automatic train stopping apparatus whereby the propelling power of the motor car will be cut off and the brakes applied in the event of the car or train entering the danger zone, wherein the apparatus will operate when the car is traveling 105 head on and rear end first and whereby the number of operations of the apparatus may be readily and quickly ascertained.

If desired, appropriate mechanism may be employed to restore the controlling valve 20 110 to normal position from the cab of the locomotive thereby eliminating the necessity of the engineer descending from the cab. In the present instance, this restoring mechanism comprises a vertical lever 52 pivoted 115 between its ends and having the upper end thereof under the control of the engineer and the lower end pivotally connected with one extremity of a horizontal rod 53 upon which is mounted a block 54 capable of sliding movement and provided with a laterally extending pin 55 passed through an opening 120 in the upper end of the arm 40. Fast upon

the rod 53 at opposite sides of the block 54 are collars 56, 67. Normally, the block 55 abuts the collar 56 and when the arm 40 moves under the action of the arm 30, as 5 previously described, the block 54 slides along the rod 53 toward the collar 57, the rod 53 swinging downwardly about its pivotal connection with the lever 52, in the sliding of the block 54. To restore the arm 10 40 and the plug of the valve 20 to normal position, the lever 52 is swinging about its fulcrum whereby the rod 53 moves rearwardly so that the collar 57 will abut the block 54 and carry the latter to normal position. If 15 necessary, a connection may be established between the rod 53 and the latch bar 42 so that the latter will be retracted in the movement of the rod 53 to restore the controlling valve.

20 While I have herein shown and described one preferred form of my invention by way of illustration, I wish it to be understood that I do not limit or confine myself to the precise details of construction herein described and delineated, as modification and variation may be made within the scope of 25 the claims without departing from the spirit of the invention.

I claim:

30 1. In train stopping apparatus, a motor adapted to cut off the propelling power of the train, a source of supply for said motor, means controlling communication between said motor and source, and means for actuating said first means to establish communication between said motor and source, said last means comprising horizontal rods movable in relatively opposite directions simultaneously, a lever fulcrumed between its ends, and connections between said rods and lever at the opposite sides of the fulcrum thereof.

2. In train stopping apparatus, a motor adapted to cut off the propelling power of the train, a source of supply for said motor, means controlling communication between said motor and source, and means for actuating said first means to establish communication between said motor and source, said last means comprising horizontal rods movable in relatively opposite directions simultaneously, a lever fulcrumed between its ends, connections between said rods and lever at the opposite sides of the fulcrum thereof, a latch for holding said first means in actuated position, and means for operating said latch to release said first means.

3. In train stopping apparatus, a fluid motor adapted to cut off the propelling power of the car, a source of supply for said motor, a valve controlling communication between said motor and source, a handle depending from said valve, horizontal rods disposed one above the other and movable

in relatively opposite directions simultaneously, said rods being disposed upon one side of said handle and each having one end in engagement with the adjacent edge of the handle, a lever fulcrumed between its ends and capable of swinging movement, and connections between the free ends of said rods and said lever at the opposite sides of the fulcrum of the latter whereby when the lever is swung in one direction or the other the rods will be actuated to open said valve. 75

4. In train stopping apparatus, a fluid motor adapted to cut off the propelling power of the car, a source of supply for said motor, a valve controlling communication between said motor and source, a handle depending from said valve, horizontal rods disposed one above the other and movable in relatively opposite directions simultaneously, said rods being disposed upon one side of said handle and each having one end in engagement with the adjacent edge of the handle, a lever fulcrumed between its ends and capable of swinging movement, connections between the free ends of said rods and said lever at the opposite sides of the fulcrum of the latter whereby when the lever is swung in one direction or the other the rods will be actuated to open said valve, and means for restoring said lever to normal position and adapted to maintain the same in such position. 80 85 90 95

5. In train stopping apparatus, a fluid motor adapted to cut off the propelling power of the car, a source of supply for said motor, a valve controlling communication between said motor and source, a handle depending from said valve, horizontal rods disposed one above the other and movable in relatively opposite directions simultaneously, said rods being disposed upon one side of said handle and each having one end in engagement with the adjacent edge of the handle, a lever fulcrumed between its ends and capable of swinging movement, connections between the free ends of said rods and said lever at the opposite side of the fulcrum of the latter whereby when the lever is swung in one direction or the other the rods will be actuated to open said valve, and springs for restoring said lever to normal position and maintaining the same in such position.

6. In train stopping apparatus, a fluid motor adapted to cut off the propelling power of the car, a second motor designed to actuate the engineer's brake valve, a source of supply for said motors, a valve controlling communication between said motors and source, a handle depending from said valve, horizontal rods disposed one above the other and movable in relatively opposite directions simultaneously, said rods being dis-

posed upon one side of said handle and each having one end in engagement with the adjacent edge of the handle, a lever fulcrumed between its ends and capable of swinging movement, and connections between the free ends of said rods and said lever at the opposite sides of the fulcrum of the latter whereby when the lever is swung in one direction

or the other the rods will be actuated to open said valve.
